UNITED STATES PATENT OFFICE.

LEWIS J. BAZZONI, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

METHOD OF AND MACHINE FOR PREPARING HEEL BREAST FLAPS.

Application filed February 6, 1928, Serial No. 252,362, and in Great Britain July 19, 1927.

This invention relates to a novel method and machine for preparing breast covering flaps for application to shoe heels.

In preparing shoe soles for the reception of some types of heels, of which the Louis heel is a conspicuous example, it is a common practice to split the heel end of a sole forward to about the line where the breast of the heel is to be positioned upon the sole, producing 10 a skiving at the grain side of the sole which skiving is left attached to the sole in the form of a flap. This flap is turned out and the heel is applied to the body portion of the sole from which the flap was split. After 15 the heel is attached, the flap is fitted as smoothly as possible to the breast face of the heel and secured thereto, usually by an adhesive paste or cement.

Such a breast covering flap, having been 20 split from a flat piece of sole leather, naturally tends to lie flat but, since it is thin and fairly flexible, it may easily be bent or curved in one direction. It is, however, quite strong and substantially elastic, consisting of the 25 grain portion of sole leather, and not only resists attempts to conform it to a surface which is curved in two directions, as are the breast surfaces of many heels, but has a marked tendency to spring away from portions 30 of such a surface, even after the flap has been pressed tightly against said surface throughout its entire area. These characteristics are very noticeable in the deep concavity in the profile of a Louis heel at each side 35 of its breast, beneath the overhanging, forwardly projecting, upper portion of the heel, and cause considerable difficulty and delay in the operation of laying and securing the breast flap to the heel.

40 An object of the present invention is to provide a method of preparing a breast flap, and a machine for use in practising the method, whereby the difficulties and disadvantages hitherto encountered may be eliminated.

45 With the foregoing in view, the invention, in one aspect, comprises a method according to which certain predetermined portions of a breast flap are stretched relatively to the remainder thereof beyond the limit of elastic 50 recovery of the material of which the flap is made. This operation is preferably carried out before the heel is applied to the shoe sole, and may be performed either before or

after the sole is attached to a shoe. By 55 stretching portions of the flap to the extent stated their fibrous structure is more or less broken down and the tendency of the flap to return to a flat condition is reduced or destroyed. Consequently, the portions to be stretched having been properly selected, a 60 flap so treated may very easily be brought into contact with the heel breast at all points and, the contacting surfaces having been previously coated with an adhesive, perfect adhesion of the flap to the heel may be secured 65 merely by a wiping, rubbing or pounding action. The tendency of the flap to draw away from portions of the heel breast having been eliminated, there is no necessity for the use of a clamping press, rubber bands, or the 70 like which have been commonly used to hold the flap pressed tightly against the heel breast for a considerable time after the flap was applied.

75 The stretching of the flap is preferably effected progressively outward from the central portion of the flap toward its lateral edges and, to this end, the method, as herein exemplified, comprises first clamping the central portion of the flap and then applying 80 stretching force which increases progressively from the central region of the flap outward, the greatest stretching force being applied at the lateral edges. Inasmuch as it is at these edges that the tendency of the flap to 85 pull away from the heel breast is most conspicuously manifest, the application of the greatest stretching force to them, resulting in the production of a flap the sides of which are permanently longer than the center, produces 90 a flap which readily conforms to the heel breast.

In another aspect, the invention comprises a machine for operating upon heel breast flaps having, in combination, means for clamping 95 the central portion of the flap and means for applying to the flap stretching force which increases progressively from the central region of the flap outward to the lateral edges. In the illustrative machine herein shown the 100 clamping and stretching of the flap are accomplished by a pair of co-operating members comprising a rigid anvil and a yielding stretching pad backed up by a recessed, rigid support. The anvil is so formed with high 105 and low portions that it will first engage the

central portion of the breast flap and the stretching pad is normally substantially flat. Consequently, as the pad and the anvil upon which the flap is positioned approach each other they act first to clamp the central portion of the flap and thereafter, as the pad is deformed to the contour of the anvil, to stretch the flap progressively from its central region outward.

10 These and other features and advantages of the invention will best be understood and appreciated by reading the following detailed description of one embodiment of the machine and one manner of using the same in the practice of the method, in connection with the accompanying drawings in which,

Fig. 1 is a front view of the machine with the work in position to be operated upon;

Fig. 2 is a side view of the upper part of the machine;

Fig. 3 is a sectional view upon the line III—III of Fig. 1;

Fig. 4 is a sectional view upon the line IV—IV of Fig. 2; and

25 Fig. 5 is a perspective view of the work after it has been operated upon.

In the drawings, 10 indicates the frame of the machine in which is adjustably secured an upright post 12, held in place by set screws 14. To the upper end of the post 12 an anvil support 16 is secured by a set screw 18. The support 16 is recessed, as shown in Figs. 1 and 4, for the reception of an anvil 20 which is rigidly secured in place by a bolt 22.

35 The anvil 20 is formed with high and low portions, as is clearly shown in Figs. 1 and 3, providing a rigid molding surface, curved both in longitudinal and transverse directions, upon which a heel breast flap may be stretched. In Fig. 3, which shows a transverse section of the anvil, it will be seen that the flap supporting surface of the anvil is higher at the center 24 than it is at the sides 26, the purpose of this formation being to facilitate the application to the flap of a stretching force which increases progressively from the central region of the flap outward to its lateral edges.

40 Arranged to co-operate with the anvil 20 is a yielding stretching pad 28 which may be made of rubber or other yielding, resilient material. The ends of the pad 28 are secured, by means of plates 30, to a rigid support 32 which is recessed, as shown at 34, to permit the central portion of the pad to yield upward. The pad support 32 is secured to a vertical stem 36 which is threaded to receive a nut 38 by means of which the pad support may be adjusted vertically with respect to a carrier 40 in which the stem 36 is mounted. The carrier 40 is secured to a slide 42 which is vertically reciprocable in guides 44 formed in the frame 10.

45 The lower end of the slide 42 is connected by a rod 46 to a spring elevated treadle (not

shown) by which the slide, and the pad 28, may be moved up or down at the will of the operator.

The under side of the pad 28 is substantially flat, with the exception of a small 70 notch 48 which minimizes the danger of displacement of the work when it is engaged by the pad.

In the performance of the method of the present invention the heel end of a shoe sole 50 is split to provide a flap 52 which is turned out and which is eventually to be applied to the breast face of a shoe heel. Either before or after the sole 50 is attached to a shoe, the outwardly turned flap 52 is placed upon the 80 anvil 20, as shown in Fig. 1, and the stretching pad 28 is lowered. In the descent of the pad 28 the central portion of the flap is first clamped between the pad and the high central portion 24 of the anvil; then, as the descent of the pad support 32 continues, the central portion of the pad yields into the recess 34, permitting the pad to conform to the shape of the rigid anvil and applying to the flap a stretching force which increases progressively from the central region of the flap outward to its lateral edges, as the said edges are forced down into the low areas 26 at the sides of the upper face of the anvil. After the stretching and molding operation upon the flap is completed the pad 28 is allowed to rise and the work is removed from the machine.

55 The operative surface of the anvil 20 is so formed that the lateral edge portions of the flap 52 are stretched beyond the limit of elastic recovery of the material of the flap and consequently, after the operation described above, the edge portions of the flap are permanently longer than the central region thereof; as shown at 54 in Fig. 5. The flap thus prepared may now very easily be brought into contact at all points with the breast surface of the heel after the heel is applied to the shoe and, the contacting surfaces having been previously coated with an adhesive, perfect adhesion of the flap to the heel may be obtained merely by a wiping, rubbing, or pounding action, there being no necessity for the use of a clamping press, 115 rubber bands, or the like, to hold the flap pressed tightly against the heel breast for a considerable time after the flap is applied.

60 Having described the invention, what is claimed as new and desired to be secured by Letters Patent is:

1. The method of preparing a breast flap for application to a heel which comprises stretching certain predetermined portions of said flap relatively to the remainder thereof beyond the limit of elastic recovery of the material of which the flap is made.

2. The method of preparing a breast flap for application to a heel which comprises stretching the lateral edge portions of said 130

flap relatively to its central portion beyond the limit of elastic recovery of the material of which the flap is made.

3. The method of treating a heel breast flap which comprises splitting the heel end of a sole to provide a breast flap, stretching the lateral edge portions of the flap relatively to its central portion beyond its limit of elastic recovery, attaching a heel to the sole, and applying the stretched flap to the breast of the heel.

4. The method of preparing a breast flap for application to a heel which comprises clamping the central portion of the flap and then applying force to stretch the margins of the flap relatively to its central portion.

5. The method of preparing a breast flap for application to a heel which comprises clamping the central portion of the flap and then stretching the flap progressively from the central region of the flap outward to its lateral edges.

6. The method of preparing a breast flap for application to a heel which comprises clamping the central portion of the flap and then stretching successive portions of the flap disposed outward from the central portion by amounts which increase progressively.

7. In a machine for operating upon heel breast flaps, the combination of means for clamping the central portion of the flap and means for applying to the flap stretching force which increases progressively from the central region of the flap outward to its lateral edges.

8. In a machine for operating upon heel breast flaps, the combination of an anvil

adapted to receive and support a breast flap, and a yielding stretching pad co-operating with said anvil to apply stretching force to certain predetermined portions of the flap sufficient to stretch said portions beyond the limit of their elastic recovery.

9. In a machine for operating upon heel breast flaps, the combination of a flap supporting anvil having high and low portions, a yielding stretching pad, and means for effecting relative approaching movement of the pad and anvil.

10. In a machine for operating upon heel breast flaps, the combination of a rigid anvil having a flap supporting surface which is higher at the center than at the sides, a yielding stretching pad, and means for effecting relative approaching movement of the pad and anvil.

11. In a machine for operating upon heel breast flaps, the combination of a rigid anvil having a flap supporting surface which is higher at the center than at the sides, a yielding stretching pad, a recessed, rigid support backing up the pad, and means for effecting relative approaching movement of the pad and anvil.

12. In a machine for operating upon heel breast flaps, the combination of a rigid anvil having a flap supporting surface which is curved in two directions, a yielding stretching pad adapted to conform to said surface, and means for effecting relative approaching movement of the pad and anvil.

In testimony whereof I have signed my name to this specification.

LEWIS J. BAZZONI.
